ATTORNEY.

Patented Dec. 22, 1925.

UNITED STATES PATENT OFFICE.

IRSIL L. G. CORNELL, OF MILWAUKEE, WISCONSIN, ASSIGNOR TO THE MILWAUKEE
BRUSH MANUFACTURING COMPANY, OF MILWAUKEE, WISCONSIN, A CORPORA-
TION OF WISCONSIN.

ROTARY BRUSH.

Application filed May 28, 1924. Serial No. 716,429.

To all whom it may concern:

Be it known that I, IRSIL L. G. CORNELL, a citizen of the United States, and resident of Milwaukee, in the county of Milwaukee, 5 and State of Wisconsin, have invented new and useful Improvements in Rotary Brushes, of which the following is a description, reference being had to the accompanying drawings, which are a part of this specification.

The invention relates to rotary brushes.

An object of the invention is to provide a rotary brush of simple construction in which the bristles are firmly held against displacement in all directions.

Another object of the invention is to provide certain improvements over the rotary brush shown in my United States Letters Patent No. 1,497,974, granted June 17, 1924.

20 The invention further consists in the several features hereinafter set forth and more particularly defined by claims at the conclusion hereof.

In the drawings, Fig. 1 is an elevation 25 view of a device embodying the invention, parts being broken away and parts being shown in section;

Fig. 2 is a section taken on the line 2—2 of Fig. 1; and

30 Fig. 3 is an expanded view of the hub. The hub of the brush comprises a centrally disposed bristle-receiving spider 12, and end clamping plates 13.

The spider 12 is a stamping made from 35 sheet metal consisting of a ring provided with a series of spaced openings 14 disposed near its outer edge and tongues 15 projecting from the inner edge of the openings, one set of tongues extending laterally 40 on one side of the ring and another set extending laterally on the other side of the ring. Bunches of bristles 16 are connected to the spider by passing them through the openings 14 and bending them to extend outwardly from the arcuate portions 17 formed by cutting or punching out the openings 14. The brush herein shown is provided with wire bristles although the bristles may be of other material if desired.

50 Each clamping plate 13 is a metal stamp-

ing provided with a set of openings 18 positioned to admit passage of one set of the tongues 15 through it, and when the bristles have been placed on the spider, they are firmly clamped to and between it and the 55 plates 13 by passing the tongues through the openings 18, and crimping their ends down upon the outer sides of the plates.

The plates 13 are somewhat larger than the spider 12 and each is provided near its outer edge with a set of laterally projecting tongues 19 punched out to extend inwardly adjacent similar tongues on the other plate when the hub is assembled. The 60 tongues 19 then form partitions for each set 65 of bristles so that there will be no displacement of the bristles in the plane of rotation of the brush. The clamping plates being larger than the spider will prevent lateral displacement of the bristles so that they will 70 be maintained in their proper radially extending position during the life of the brush.

A central bushing for the brush is formed 75 of bearing metal 20 which is permitted to flow in between the plates and spider, as shown in Fig. 2, so as to firmly anchor it to the hub. The metal fills all unoccupied place between the plates and spider and adjacent the bristles to prevent their displacement at their inner ends.

The invention provides a rotary brush of simple construction in which the bristles are firmly secured against displacement in 80 all directions.

What I claim as new and desire to secure by Letters Patent is:

1. In a rotary brush, the combination of a spider having a series of bristle receiving openings near its outer edge, bristles passed 90 through said openings and extending back on themselves and outwardly in substantially radial position, tongues on said spider extending laterally therefrom, plates 95 against which the outer ends of said tongues are bent to clamp the bristles between the plates and against the spider, and tongues on said plates extending laterally inwardly in adjacent relation beyond the outer edge of the spider to prevent displacement of said 100

bristles in the plane of rotation of the brush.

2. In a rotary brush, the combination of a spider having a series of bristle-receiving openings near its outer edge, bristles passed through said openings and extending back on themselves and outwardly in substantially radial position, plates secured to the said spider at each side and clamping the

bristles between them and the spider, and tongues on said plates extending inwardly ¹⁰ beyond the outer edge of the spider to prevent displacement of said bristles in the plane of rotation of the brush.

In testimony whereof I affix my signature.

IRSIL L. G. CORNELL.
